CLAIM

The ornamental design for a food mixer, as shown.

DESCRIPTION

FIG. 1 is a first embodiment of a right perspective view of a food mixer showing our new design;

FIG. 2 is a left perspective view thereof;

FIG. 3 is a top view thereof;

FIG. 4 is a bottom view thereof;

FIG. 5 is a right side view thereof;

FIG. 6 is a left side view thereof;

FIG. 7 is a rear view thereof; and

FIG. 8 is a front view thereof.

FIG. 9 is a right perspective view of a second embodiment of a food mixer showing our new design;

FIG. 10 is a left perspective view thereof;

FIG. 11 is a top view thereof;

FIG. 12 is a bottom view thereof;

FIG. 13 is a right side view thereof;

FIG. 14 is a left side view thereof;

FIG. 15 is a rear view thereof; and,

FIG. 16 is a front view thereof.

1 Claim, 8 Drawing Sheets(56)
